(57) **CLAIM**

The ornamental design for a high-speed train, as shown and described.

DESCRIPTION

FIG. 1 is a perspective top view showing a high-speed train, of the new design;

FIG. 2 is a perspective bottom view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a front elevation view thereof; and,

FIG. 8 is a rear elevation view thereof.

The grey shaded and generally horizontally extending band denotes a darker contrast in appearance as compared to the areas outside this band.

1 Claim, 8 Drawing Sheets
